UNITED STATES PATENT OFFICE.

FRED C. MINTIE, OF CHICAGO, ILLINOIS.

DESIGN FOR A BUTTON.

47,734.

Specification for Design.

Patented Aug. 17, 1915.

Application filed April 26, 1915. Serial No. 24,164. Term of patent 3½ years.

To all whom it may concern:

Be it known that I, FRED C. MINTIE, a citizen of the United States, residing at Chicago, in the county of Cook and State of Illinois, have invented a new, original, and ornamental Design for Buttons, of which the following is a specification, reference being had to the accompanying drawings, forming a part thereof.

I claim—

The ornamental design for a button as shown.

FRED C. MINTIE.
